UNITED STATES PATENT OFFICE.

GORDON SPENCER MARSTON, OF RAVENSCOURT PARK, ENGLAND.

DRIP-PREVENTER AND THE LIKE.

1,351,258.

Specification of Letters Patent. Patented Aug. 31, 1920.

Application filed May 4, 1920. Serial No. 378,900.

To all whom it may concern:

Be it known that I, GORDON SPENCER MARSTON, a subject of the King of Great Britain and Ireland, and resident of Ravenscourt Park, in the county of Middlesex, England, have invented new and useful Improvements in or Relating to Drip-Preventers and the like, of which the following is a specification.

10 This invention relates to improvements in drip preventers and the like, and it has for its object to provide means for preventing liquid from running down the outside of or dripping from the end of a pouring spout of 15 a liquid containing vessel during and after the pouring operation.

According to the present invention, means for this purpose comprises a member loosely supported by the spout so as to hang substantially vertical whatever the position of 20 the vessel.

25 Preferably, the member is loosely carried on, for example, is hinged to, a member secured to the spout, for example, a spring member secured in the spout.

The invention will now be described with reference to the accompanying drawings wherein:—

30 Figure 1, is a perspective view of a portion of the spout of a domestic vessel, showing an embodiment of my invention applied thereto, the spout being partially broken away to show hidden portions.

35 Fig. 2 is also a perspective view of portion of a spout having a modified form of my invention applied thereto and partially shown by dotted lines.

40 Referring to Fig. 1, a metal strip is bent to lie within the spout 3, of, for example a teapot, and one end is cut longitudinally, the two portions 2 being opened out so that when the strip is inserted in the spout the portions 2 bear against the inside of the spout and the strip is held in position. The 45 other end of the strip 1 overhangs the edge of the spout and to it is hinged a tapered strip 4.

45 The construction shown in Fig. 2, is made of twisted wire which is bent into a loop 5, which forms a stop, and has a rearwardly extending portion which is opened out and bent as shown at 6, 6 to secure it within the spout 3. To the other end and below the loop 5 is attached a chain 7 which overhangs 55 the edge of the spout as shown.

When pouring liquid, the portions 4 or 7

always assume a vertical position so that the liquid is guided by them and is prevented from running down the outside of the spout, and at the completion of the pouring operation, dripping is prevented by capillary action.

The devices according to the present invention, should be of a non-corroding material, such for example as silver.

It is to be understood that various modifications may be made without departing from this invention, for example, instead of a chain the member overhanging the lip of the pouring spout may be a coiled spring, 70 loosely attached to the supporting member carried in the spout; or the supporting member may be secured outside the spout.

What I claim is:

1. Means for preventing liquids from running down the outside of the pouring spout of a liquid-containing vessel comprising a member to be carried by the spout and a second member loosely attached to the first mentioned member so as to be free to move 80 and maintain a substantially vertical attitude, whatever the position of the vessel.

2. Means for preventing liquids from running down the outside of the pouring spout of a liquid-containing vessel comprising a member to be carried by the spout and a second member hinged to the first mentioned member so as to be free to move and maintain a substantially vertical attitude, whatever the position of the vessel.

3. Means for preventing liquids from running down the outside of the pouring spout of a liquid-containing vessel comprising a member to be carried by the spout and a second member comprising a chain loosely attached to the first mentioned member and which overhangs the edge of the spout so as to be free to move and maintain a substantially vertical attitude whatever the position of the vessel.

4. Means for preventing liquids from running down the outside of the pouring spout of a liquid-containing vessel, comprising a member to be inserted in the spout having one end shaped so as to bear against the inside of the spout to secure it therein, and a second member loosely attached to the first mentioned member so as to be free to move and maintain a substantially vertical attitude, whatever the position of the vessel.

Dated this 20th day of April, 1920.

GORDON SPENCER MARSTON.
